CLAIM

The ornamental design for a plastic bottom clasp for paper hanger, as shown and described.

DESCRIPTION

FIG. 1 is a front perspective view of a plastic bottom clasp for paper hanger in the open position showing our new design;

FIG. 2 is a rear perspective view thereof;

FIG. 3 is a front elevation view thereof;

FIG. 4 is a rear elevation view thereof;

FIG. 5 is a right side elevation view thereof;

FIG. 6 is a sectional view thereof;

FIG. 7 is a top view of the plastic bottom clasp for paper hanger of FIG. 1;

FIG. 8 is a bottom view thereof;

FIG. 9 is a front perspective view of the plastic bottom clasp for paper hanger in the closed position;

FIG. 10 is a rear perspective view thereof;

FIG. 11 is a front elevation view thereof;

FIG. 12 is a rear elevation view thereof;

FIG. 13 is a right side elevation view thereof;

FIG. 14 is a sectional view thereof;

FIG. 15 is a top view of the plastic bottom clasp for paper hanger of FIG. 9; and,

FIG. 16 is a bottom view thereof.

The evenly-dashed broken line is for the purpose of illustrating environmental structure and forms no part of the claimed design. The dot-dot-dash broken line defines the bounds of the claimed design and forms no part thereof.
